METHOD OF AND APPARATUS FOR ROAD CONSTRUCTION

James Norman Byrd, Baltimore, Md., assignor of one-third to Charles F. H. Foard and one-third to Paul B. Wolf, both of Baltimore, Md.

Application January 6, 1931, Serial No. 507,009

9 Claims. (Cl. 94—44)

This invention relates to a method of and apparatus for road construction.

In order to thoroughly understand and realize the importance of my invention in the progress of 5 improving road construction, consideration must be given to the present day methods and apparatus, particularly in reference to the bituminous types of roads.

There are most generally used two methods of 10 bituminous road construction, namely the penetration method and the hot mechanical mix method.

The penetration method consists briefly in spreading the desired thickness of cold, dry aggregate on a suitable foundation, then compressing the same, after which hot bitumen is sprayed or poured over the aggregate in sufficient quantity to run or leak through the interstices thereof and coat and bind the aggregate. A top finishing 20 may then be applied in the form of smaller sized aggregate and bitumen.

Investigation and analysis of the penetration method have shown that there exist many disadvantages incident thereto, the basic and most 25 prevalent of which is the failure of the bitumen to entirely seep through the aggregate and to completely coat each fragment thereof. The reason for this is quite obvious. When the hot bitumen is sprayed or poured over the cold aggregate its viscosity becomes more pronounced, even under favorable weather conditions, and if exposed to normal winter temperatures and brought into contact with the cold aggregate, it will approach a solid condition. Under the best 30 circumstances the seepage of the bitumen will not extend entirely through the compressed aggregate and will only coat the portions of the fragments of aggregate abutting the interstices. The results are that the aggregate is not thor- 35oughly subjected to a binding agent and under the stress of traffic and use, it will shift relative to the foundation of the road; water and freezing weather will cause displacement of the aggregate; and, necessarily, repeated repairs must be made 45 with excessive maintenance charges.

The hot mechanical mix method consists briefly in transporting the aggregate to a mixing plant where it first is dried, heated to and maintained at the necessary temperature, then mixed with 50 a predetermined amount of hot bitumen, and subsequently hauled to the point of operation where it is spread over the road foundation and compressed. This method requires the initial investment of a plant, storage bins, heating and mixing 55 apparatus, transportation facilities and the nec-

essary amount of labor for operations. Naturally, the use of the method in question is limited to territories where plants of the type described are located and the expenses appertaining thereto are excessive and in the majority of cases prohibitive.

My method of and apparatus for road construction is designed to overcome the aforementioned disadvantages relative to the two methods of 60 road construction discussed and to offer advantages and results heretofore unknown.

One of the objects of my invention is to provide a method of and apparatus for road construction which will so thoroughly commingle the ingredients of a bituminous type of road, namely 70 aggregate and bitumen, that each and every fragment is completely coated from the top of the layer to the very foundation, the ultimate effect being to completely bind the aggregate into a substantially solid mass.

Another object of my invention is to provide a method of and apparatus for road construction which will allow, when mixed with bitumen, the use of a variety of materials as ingredients of a bituminous type of road, such as many kinds of 80 stone, slag, gravel, shell and the like. This is highly advantageous, particularly in rural districts, since it will be unnecessary to transport the usual type of aggregate now used to a point of operation where there exists such aforementioned material.

Another object of my invention is to provide a method of and apparatus for road construction which materially reduces the cost of a bituminous type of road, that is, by eliminating approximately more than one-half of the labor now required and by reducing the amount of ingredients now used. It has been found that because of the thorough commingling of the ingredients, a better result than now obtained can be had by using 95 less aggregate and only about one-half of the usual quantity of bitumen.

Another object of my invention is to provide a method of and apparatus for road construction which will produce a road of a bituminous type, 100 a great deal more quickly per square foot than by any method heretofore used. Actual experiments have proven that where the hot mechanical mix method produces approximately two thousand square yards per day, my invention will 105 produce approximately ten thousand square yards per day.

Another object of my invention is to provide a method of and apparatus for road construction which can operate under all weather conditions, 110

particularly in cold weather, and on all kinds of surface conditions, whether the foundation of the road is dirt, rock, shale, or an old macadam, concrete, or bituminous road, as well as gravel or sand.

Still another object of my invention is to provide a method of and apparatus for road construction which will reduce the actual apparatus necessary in building a bituminous type of road, 10 since my apparatus comprises a single machine which continuously performs the several operations simultaneously. The machine, which is simple in construction, is exceedingly sturdy and efficient and the manufacturing cost thereof is exceptionally small.

With these and other objects and advantages in mind, attention is called to the drawings where there is shown the apparatus used in my method of road construction, and in which:

20 Figure 1 is a side elevation of the machine.

Figure 2 is a back view of the machine.

Figure 3 is a plan view of the machine.

Figure 4 is a detailed elevation of one type of mixing blade used.

25 Figure 5 is a detailed elevation of another type of mixing blade used.

Figure 6 is a detailed elevation of the side blades used.

Figure 7 is a detailed elevation of the series 30 of curved spreading blades used, and

Figure 8 is a diagrammatic view of the arrangement of mixing blades, spreading blades and the levelling blade.

Referring particularly to the drawings, in 35 which like numerals indicate like parts, a super-structure frame comprises upwardly curved bars 1 and 2, which converge slightly toward their front ends where they are joined in any suitable manner by a cross plate 3, and which diverge 40 slightly toward their rear ends and are secured in any suitable manner to a frame 4, upon which is supported a platform. A king pin 5 extends through the cross plate 3, and rotatably holds the U-shaped axle frame 6. An axle 7 is held 45 by the ends of frame 6, and has at each end a wheel 8. A tongue 9 is secured to the U-shaped axle frame to facilitate attachment to a power propelling means, such as a tractor. It will be noted that the axle and wheels may be turned 50 beneath the super-structure frame, thereby allowing a comparatively short turning radius for the machine.

The frame 4 is supported by wheels 10, mounted on axle 11, secured thereto, and comprises the 55 side bars 12, front end bar 13, and a rear end bar 14. Cross bars 15 extend between the side bars 12 to add rigidity to the frame.

Secured on the front end of frame 4, and at each end thereof, is a support 16 having a housing 60 in which are mounted worm gears 17, provided with adjusting wheels 18. Above the worm gear housings are brackets 19 which hold shafts 20 at the ends of which are gear wheels 21, meshing with said worm wheels. The other ends of shafts 65 20 are rotatably held in brackets 22, attached to the sides of the curved bars 1 and 2. Adjacent the brackets 22, the said shafts are bent outwardly, as at 23, and at their ends are provided with closed hook members 24, in which are suspended the arms 25, said arms movably supporting 70 a blade holding frame.

Extending from and secured to the king pin 5 is an arm 26, and extending from and secured to the lower side of cross blade 3 is an arm 27 75 between which there is held a pin 28. Two bars

30 and 31 converging at their front ends are slidably held by pin 28, and diverge as they extend rearwardly and horizontally as at 32, then obliquely as at 33, and finally horizontally as at 34. At the rearmost ends of said bars are vertically positioned angle bars 35, having apertures 80 therein.

The blade holding frame comprises front end member 36, side members 37, which have angle bars 38 with apertures therein vertically positioned at their rearmost ends, and cross members 39, 40, 41 and 42. To the portions 34 of bars 30 and 31 are secured the cross members 39, 40, 41 and 42. The arms 25 are attached to the blade holding frame in any suitable manner, 90 such as brackets 43.

It will thus be observed that the blade holding frame is adjustably suspended from the super-structure, and is held for vertical movement only by means of the bars 30 and 31.

95 The mixing blades are secured beneath, and to the blade holding frame, and comprise two types which are shown in detail in Figures 4 and 5. These blades are interchangeable, but I have found the type shown in Fig. 4 to be preferable as front blades, while the type shown in Fig. 5 is preferable as rearwardly disposed blades.

The blade shown in Fig. 5 comprises a round snub nose 43' and diverging sides 44, with suitable means, such as plate 45 for attachment to the blade-holding frame. It will be noted that the nose 43' extends above the sides 44, and that said sides are flared at their tops and bottoms to effect a substantially concave surface.

The blade shown in Fig. 4 comprises a pointed 110 nose 46, which turns slightly upwardly at its base, recedes rearwardly, and curves upwardly, so that the top portion overhangs the center of the curved portion of the blade. The sides 47 of the blade diverge rearwardly and are flared 115 at the tops and bottoms thereof to effect a substantially concave surface. Suitable means, such as plate 48 and rod 49 are provided for attaching the blade to the blade-holding frame.

The side blade, shown in Fig. 6, comprises a 120 concaved portion 50, having a suitable means, such as a plate 51 for attaching the blade to the blade holding frame.

The front mixing blades shown in Fig. 4, are 125 two in number, and are attached to the blade-holding frame by means of the plates 45 secured to bars 52, which span the front end member 36 and cross members 39, 40 and 41, and are attached thereto.

The remaining mixing blades of the type shown 130 in Fig. 5, are six in number, two of which are attached to cross member 40, two of which are attached to cross member 41, and two of which are attached to cross member 42 by means of plates 48 and rods 49, the latter elements being secured to the preceding cross members.

The positioning of the mixing and side blades 135 on the mixing blade holder heretofore described is of the greatest importance. It will be noted that the mixing blades are placed in staggered 140 relationship to each other, and attention is called to Fig. 8, where a diagrammatic view of the positions of the blades is disclosed. The line A—A in Fig. 8, designates a central longitudinal division of the machine.

145 Looking from the rear to the front of the machine, the right hand front mixing blade is placed adjacent and to the right of the line A—A, and the left hand front mixing blade is placed between the left hand side member of the blade 150

holding frame and the line A—A. In the second row the right hand mixing blade is placed between the right hand side member of the blade holding frame and line A—A, and the left hand 5 mixing blade is placed adjacent and to the left of the line A—A. The relative positions of the third row of mixing blades corresponds to that of the front row of mixing blades, and the fourth row of mixing blades to that of the second row 10 of mixing blades. It will thus be observed that the second and fourth rows of mixing blades are in staggered relationship to the first and third rows of mixing blades.

The side blades, of which there are four, are 15 attached to the side members of the blade holding frame, and are positioned as follows:

Looking from the rear to the front of the machine, the front right hand side blade is placed between the front end member 36 of the blade-holding frame and cross member 39, and the rear 20 right hand side blade is placed between cross members 40 and 41; the front left hand side blade is placed between cross members 39 and 40, and the rear left hand side blade is placed between cross members 41 and 42. It will be 25 noted that the side blades are positioned at an angle relative to the longitudinal axis of the machine with their front ends outwardly disposed.

The reasons for the position of the blades as 30 described, and the importance thereof, will later be set forth in detail.

The spreading blades shown in detail in Fig. 7, are adjustably positioned at the rear of the blade-holding frame, and comprise three curved 35 blades 53, 54 and 55, which are secured to the bar 56, upon which are mounted vertically positioned angle bars 57, having apertures therein. The angle bars 57 coincide with the angle bars 38 vertically disposed at the rearmost ends of the 40 blade-holding frame side members 37 and the angle bars 35 vertically disposed at the rearmost ends of the bars 30 and 31. By virtue of the apertures and bolts used therewith in the aforementioned angle bars, the spreading blades may 45 be vertically adjusted relative to the blade holding frame in the desired position. As observed in Fig. 8, curved blade 53 is disposed at the right hand side of the machine, looking from the rear to the front thereof, and extends from a point 50 outside of the blade holding frame to a point in line with the right hand front mixing blade, from which point the curved blade 54 extends to a point in line with the left hand front mixing blade, and from which point the curved blade 55 55 extends to a point outside of the blade-holding frame. The purpose and the importance of such an arrangement of spreading blades will be later discussed in detail.

The leveling blade is positioned beneath the 60 frame 4 and behind the wheels 10. It comprises a portion 58 to which is secured, in any suitable manner, a curved portion 59, and extends transversely of the machine slightly beyond the width of the rear wheels and the mixing blade holding frame.

A plate 60 is held at its front end in any suitable manner, such as a rod 61, loosely positioned in a plate 62 attached to the axle 11, and secured at its rear end to a bar 63. Underneath said plate 70 and at both sides thereof are provided slightly curved guides 64, against which the top of the leveling blade rests. A brace 65 is centrally positioned on top of plate 60, and through said brace and plate extends the bolt 66, to which 75 is pivoted the leveling blade. The bar 63 is sup-

ported by adjusting rods 67, which are screw threaded and are held in sleeves 68. Adjusting wheels 69 cooperate with the rods 67 to lift or lower the leveling blade. A locking means for the vertical adjustment of the leveling blade may be provided, such as arms 70, secured to the bar 63 at 71, and extend through the side bars 12, where they are supported by sleeves 72. The said arms are screw threaded and are provided with wheels 73 which, when tightly screwed against the sleeves 72, prevent vertical movement of the adjusting rods 67.

Pivottally held adjacent the top of the leveling blade and at both sides thereof are bars 74, which extend forwardly through slots in plates 75, attached to the axle 11. The said bars are provided with holes 76 to accommodate pins 77. Braces 78, secured underneath the bars 74, are attached to the lower part of portion 58 of the leveling blade.

It will be observed that by means of the bars 74 the leveling blade may be adjustably positioned transversely of the machine, as required.

Before explaining the operation of the machine in conjunction with my method of road construction, attention is called to the fact that there are many and various changes and substitutions which can be made and are contemplated relative to the detailed structure of the machine, and within the scope of the invention.

My method of road construction in which the apparatus above described is utilized, involves and consists of laying on the foundation of the road or upon the surface of an old worn out macadam or bituminous road the desired amount of aggregate over which a predetermined amount of comparatively cold bitumen is spread. The machine is then propelled over the road and the aggregate and bitumen is thoroughly mixed in situ, spread evenly over the road surface, and levelled properly 110 from the sides to the crown of the road. Stone, chips, or smaller aggregate may then be spread over the thoroughly mixed aggregate and bitumen to fill up the voids therein, after which compression is applied to the road. A final seal coat 120 of bitumen and fine aggregate may be laid, and the road is opened to traffic.

The term "aggregate" is used to include the various types of stone, slag, gravel, shell, and the like, which may be used, and the amount which 125 is laid on the foundation of the road depends, of course, on external conditions, such as the traffic burden, grade, weather conditions of the particular territory, and the like.

The amount of bitumen required is predetermined by the type and amount of aggregate used.

The thorough commingling of the aggregate and bitumen which results in the coating of each and every fragment of aggregate so that perfect adhesion is obtained, allows the use of a smaller amount 135 of both aggregate and bitumen and yet produces a substantially solid material. At the same time it is not necessary that the aggregate or bitumen when applied be hot or in a heated state, as is the case where the usual method of bituminous road building is used.

The thorough commingling in situ of the aggregate and bitumen is accomplished by the mixing blades of the machine and their particular staggered arrangement.

Attention is directed to Figure 3 and the diagrammatic drawing in Figure 8. The first and third rows of mixing blades are positioned off center toward the left hand side of the machine as it moves forwardly, and consequently away 150

from the curb or road side toward the road crown. The second and fourth rows of mixing blades are positioned in staggered relationship to the first and third rows. It will be observed that the ends 5 of the diverging sides of each blade except the last row, point substantially at the noses of the mixing blades following.

When the machine is ready for operation, the blade holding frame is lowered to the depth of the aggregate by means of the adjusting wheels 18. As the machine starts, the rounded noses of the front mixing blades will be forced into the aggregate and bitumen to a point approximately scraping the road foundation. The diverging and concaved sides of the front blades will pick up the aggregate and bitumen adjacent thereto, turn it over, and deposit it directly in front of the noses of the mixing blades following so that the displacement of the aggregate and bitumen from 15 where originally deposited is comparatively slight. The tendency of the front mixing blades, due to their positions relative to the road, is to cause the slight displacement to be toward the road crown and away from the road curb or side. The 20 second row of mixing blades, with their slightly upturned and receding noses, will penetrate the turned over aggregate and bitumen and due to the concaved and diverging sides thereof, the material is again turned over. The process is repeated as described by each row of blades. In 25 order that the second, third, and fourth rows of mixing blades will not dig into the foundation, the lower portion of the noses are slightly turned up as shown in Figure 4. The receding portion 30 of the noses of these blades do not lift the aggregate and bitumen to the extent caused by the rounded noses of the front blades but force the material rearwardly and bring about a quicker turning thereof.

40 The effect of the turning of the material by each blade is in reality a churning and violent agitation of the aggregate and bitumen with only slight displacement so that the ingredients are so thoroughly commingled that each fragment of the aggregate is entirely coated with sufficient 45 bitumen to cause perfect adhesion between the particles from the very foundation to the surface of the road.

The side blades are arranged to prevent any 50 material from being forced outside of the path covered by the mixing blades. It will be noted that each side blade is concaved and positioned with its rearmost end pointing substantially toward the noses of the mixing blades in order that 55 the material turned over by the outer diverging sides of the outside mixing blades will be directed toward the noses of the following mixing blades, and their concaved shape will also cause the aggregate and bitumen to be turned over before coming into contact with the following 60 mixing blades.

The spreading blades 53, 54 and 55 follow the mixing blades and are adjustably supported at the rear end of the mixing blade holding frame. 65 The adjustment usually made positions the bottoms of the blades slightly above the bottoms of the mixing blades. However, this adjustment depends upon the thickness and consistency of the aggregate. The purpose of these blades is 70 to evenly spread the material after the mixing operation has been completed. The shape and arrangement of the spreading blades are such as to prevent the material from becoming piled up in any one place and to evenly distribute the aggregate and bitumen.

The large blades 53 and 54 are directly behind the two rearmost mixing blades and receive the agitated material from the diverging sides thereof, while the small blade 55 receives the agitated material from the side blade adjacent thereto. It will be noted that the large blade 53 is adjacent 80 the road curb or side to assure no loss of material in that direction.

The levelling blade positioned at the rear of the machine is vertically and transversely adjustable relative to the machine. After the mixing and spreading operations have been completed, this blade levels and smooths out the material to the desired thickness of the road. Its vertical adjustment is made to determine the depth of the aggregate and bitumen, and its transverse adjustment is made so that whatever excess material over the desired thickness exists, will be spread evenly from the road curb or side to the road crown. The ends of the levelling blade extend 90 beyond the rear wheels so that any depression made thereby will be filled up and levelled off.

The operator of the machine stands upon the platform and by means of the adjusting wheels controlling the mixing blade holding frame and 100 levelling blade, has complete control over the various adjustments.

The machine shown is constructed to be propelled by means of a tractor or truck, but it is possible to provide the machine, of course, with 105 propelling means attached to the rear wheels, which could be ribbed for traction, such as a motor.

The method of road construction and the machine used therewith is continuous in that the 110 various operations, such as thorough commingling of the ingredients by churning and violent agitation, is followed immediately by the spreading operation and subsequently, immediately by the levelling operation. It has been found in actual 115 experimentation and use to be exceedingly practical. The elimination of labor and material costs have made the method of road construction very valuable and most desirable.

I am aware that there have been heretofore 120 constructed and used machines for road building purposes which by means of a series of long blades disposed transversely of the machine at various angles sweep the road material back and forth across the width of the road. These machines, 125 however, do not operate on the same theory and principle as my machine and do not accomplish the thorough commingling of the ingredients in situ with comparative slight displacement thereof.

It is obvious that there are various modifications and changes which may be made in the method and in the structure of the machine without departing from the spirit and scope of the appended claims.

I claim:

1. In a machine for road construction, a mobile supporting frame, a second frame suspended therefrom, a plurality of rows of mixing blades secured to said second frame, said rows extending 140 longitudinally of the machine in staggered relationship to each other to deflect and simultaneously rotate the materials of which the road is to be built back and forth in a state of constant agitation with relatively slight displacement of 145 the materials between lines bisecting the said rows of mixing blades.

2. In a machine for road construction, a mobile supporting frame, a second frame suspended therefrom, a plurality of rows of substantially 150

- angular mixing blades secured to said second frame, said rows extending longitudinally of the machine in staggered relationship to each other to deflect and simultaneously rotate the materials 5 of which the road is to be built back and forth in a state of constant agitation with relatively slight displacement of the materials between lines bisecting the angles of said mixing blades.
3. In a machine for road construction, a mobile supporting frame, a second frame adjustably suspended therefrom, a plurality of rows of mixing blades having diverging and concaved sides to deflect and rotate road material extending longitudinally on said second frame in staggered relationship to each other, and means to keep the material within the path of advance. 10
4. In a machine for road construction, a mobile supporting frame, a second frame adjustably suspended therefrom, a series of mixing blades having diverging and concaved sides to deflect and rotate road material secured in staggered relationship to said second frame, means to keep the material within the path of advance, adjustable means secured to said second frame to spread 15 the material to an even depth, and adjustable means secured to said supporting frame to level the material to the desired thickness.
5. In a machine for road construction, a mobile supporting frame, a second frame adjustably suspended therefrom, a series of mixing blades secured thereto at points longitudinally and transversely staggered relative to said second frame, side blades secured to said second frame to keep the material of which the road is to be built within 20 the path of advance, and means provided at the rear of said mixing blades to spread the material to an even depth.
6. In a machine for road construction, a mobile supporting frame, a second frame adjustably suspended therefrom, a series of mixing blades hav- 25
- ing diverging and concaved sides secured thereto at points longitudinally and transversely staggered relative to said second frame, concaved side blades secured to said second frame to keep material of which the road is to be built within the path of advance and impart a rotary movement thereto, curved spreading blades adjustably secured to said second frame, and a blade secured to said supporting frame to level the material to the desired thickness. 30
7. In a machine for road construction, a mobile supporting frame, a second frame adjustably suspended therefrom, a series of mixing blades having diverging and concaved sides secured thereto at points longitudinally and transversely staggered relative to said second frame, concaved side blades secured to said second frame to keep material of which the road is to be built within the path of advance and impart a rotary movement thereto, curved spreading blades adjustably secured to said second frame, and a vertically and transversely adjustable blade secured to said supporting frame to level the material to the desired thickness. 35
8. In combination with a mixing blade holding frame for road construction machines, a plurality of longitudinally extending rows of mixing blades arranged at staggered points thereon, said blades being constructed to deflect back and forth in constant agitation and simultaneously rotate the material of which the road is to be constructed. 40
9. In combination with a mixing blade holding frame for road construction machines, a series of annular mixing blades arranged thereon, the sides of said blades diverging rearwardly and being concaved to deflect back and forth in constant agitation and simultaneously rotate the material of which the road is to be constructed. 45
